CLAIM

The ornamental design for an ostomy device assembly, as shown and described.

DESCRIPTION

The file of this patent contains at least one drawing/photograph executed in color. Copies of this patent with color drawing(s)/photograph(s) will be provided by the Office upon request and payment of the necessary fee. The color shown in the drawings is not an integral feature of the claimed ornamental design.

FIG. 1 is an enlarged rear view of the cap portion of the ostomy device assembly showing our new design with the cover removed for clarity and the bag in an undeployed configuration;

FIG. 2 is front left perspective view thereof;

FIG. 3 is front left perspective view thereof;

FIG. 4 is a top view thereof;

FIG. 5 is a bottom view thereof;

FIG. 6 is a front right perspective view thereof;

FIG. 7 is a left side view thereof, a right side view being a mirror image thereof;

FIG. 8 is a rear right perspective view of the cap portion of the ostomy device assembly showing our new design with the bag in a deployed configuration but with the cover portion removed;

FIG. 9 is a rear view thereof;

FIG. 10 is a rear right perspective view thereof;

FIG. 11 is a bottom view thereof;

FIG. 12 is a front view thereof;

FIG. 13 is a top view thereof;

FIG. 14 is a right side view thereof;

FIG. 15 is a front view of the ostomy device assembly in the fully assembled state;

FIG. 16 is a right side view thereof;

FIG. 17 is a rear view thereof;

FIG. 18 is a left side view thereof;

FIG. 19 is a front left perspective view thereof;

FIG. 20 is a partial enlarged front perspective view, taken from box 20 in FIG. 6, showing our new design with the cover portion removed; and,

FIG. 21 is a partial enlarged rear perspective view, taken from box 21 in FIG. 1, showing our new design.

The broken lines of the B. Braun logo shown in FIGS. 15 and 19 depict environmental subject matter and form no part of the claimed design.

The dot-dash broken line boxes are included in FIGS. 1, 6, 20, and 21 for the purpose of illustrating the partial enlarged views and form no part of the claimed design.
